State of Pennsylvania.

Letters Patent.

The schedule referred to in these Letters Patent and making part of the same
containing a description in the words of the said Noah Morrison & John
Lewis themselves of their improvement in the machine for washing clothes
which they denominate, the Horizontal double Washing & Scouring Machine

To all to whom these presents shall come -

Be it known that We Noah Morrison and John Lewis of the Borough of
Uniontown in the County of Fayette & State of Pennsylvania, have invented
a new and useful improvement in a Machine for washing clothes, called
the Horizontal double dasher Washing and Scouring Machine & that the
following is a full and exact description of the construction and operation
of said Machine as invented or improved by us -

It consists of a Chest or box four feet in length, one foot six inches in
width and thirteen inches in depth, that is in the clear, or measuring its
inner surfaces - but in this may be varied at pleasure provided the machine
may within as to size in a corresponding ratio. It is contemplated that
the chest shall stand upon legs or feet, of any length to suit the con-
venience of the place or the operator. The chest is made perfectly tight
with a false bottom, at three fourths of an inch above the true one, this false
bottom to be perforated with small holes, so as to admit the water, washing
or dirt to descend through them, the false bottom horizontally at each end
with an apex or circle rising from it and convex with a Radius
of three inches until it equals one fourth of an entire circle, the ends
are from the apex, continued by a circular bust of nine inches Radius
formed of perpendicular ribs with intervals between them of one fourth of
an inch high or more - These ribs are fastened at top and rest
against the apex so as to have a slight spring in working the springing
busts, the ribs extending behind the machine into the space below the false

bottom, so as to allow the water, sediment, or dirt to remain as before mentioned. The chest is closed with folding lids, so as to retain the heat or steam and prevent leakage or slop. Within the chest, or box near its center but may be inclined toward one end or the other is placed a double wheel formed of iron or other metal, upon a spindle resting on guides in opposite sides of the chest, or box with two pitons in length one foot each, but which may be shortened or lengthened if necessary.

To each of these Pitons is annexed a Dasher, formed of wood and so shaped they give a Horizontal motion but in opposite directions, so that when one glides to the right, the other moves to the left, and vice versa.

The Dashers are formed of wood two feet nine inches in length at bottom and one foot three inches at top, and slopes from the upper surface to each end with notches at bottom and top of slopes.

The depth of dashers should be eight inches and the width one half and of the width of the chest, or box, or about nine inches allowing sufficient space for them to pass each other without friction, the faces of the dashers are ribbed. A play at bottom serves to draw the water and sediment as often as necessary. The dashers glide over the false bottom upon rollers inserted between, so as to bring the lower part of the dasher nearly in contact with the false bottom, and better to be placed on an iron, steel or brass trough. The spindle passes through the side of the chest in front, on its end is fitted a cog wheel six inches in diameter, but may be increased or reduced in size, and at the proper distance is attached to the side of the chest, another cog wheel whose diameter is one foot, but it may be increased or reduced at pleasure, as an increase or decrease of motion is desired and which unites with and gives motion to the upper wheel.

The larger wheel is turned by a crank or arm of one foot in length but may be increased or diminished. In place of a cog wheel motion can be given to the machine by means of a stiff iron tube or cylinder as may be preferred, clothes prepared to be washed are placed in either end of the chest and by turning the crank or arm a quick motion is given to the Dashers. The clothes are passed against the dashers in turns, and by the force of the motion of the dashers

made to receive so as to prevent in succession every part to the contact of the dashers, and thus are speedily cleaned without injury. The same principle may be applied to the machine so as to act for use at one end of the box only.
